No. 886,653.

PATENTED MAY 5, 1908.

F. C. SCHWEDTMAN.
SASH WEIGHT.
APPLICATION FILED OCT. 26, 1907.

UNITED STATES PATENT OFFICE.

FERDINAND C. SCHWEDTMAN, OF ST. LOUIS, MISSOURI.

SASH-WEIGHT.

No. 886,653.

Specification of Letters Patent.

Patented May 5, 1908.

Application filed October 28, 1907. Serial No. 399,350.

To all whom it may concern:

Be it known that I, FERDINAND C. SCHWEDTMAN, a citizen of the United States, residing at St. Louis, Missouri, have invented a certain new and useful improvement in Sash-Weights, of which the following is a full, clear, and exact description, such as will enable others skilled in the art to which it appertains to make and use the same, reference being had to the accompanying drawings, forming a part of this specification, in which—

This invention relates to a new and useful improvement in sash weights of that class wherein a metal shell or housing is employed to incase the material of which the weight is essentially composed.

My present invention relates particularly to the manner of forming the end portions 20 of the shell for housing.

Figure 1 is a side elevational view, partly in section, of my improved sash weight; Fig. 1^a is a sectional view of the cord-securing clip; Fig. 2 is a sectional view on the line 2—2 of Fig. 1; Fig. 3 is a sectional view on the line 3—3 of Fig. 1; Fig. 4 is an end view of the tube constituting the shell or housing of my improved weight; Fig. 5 is an end view showing the tube or housing with two 30 of its walls crimped, the dotted lines indicating how the remaining walls are folded in; Fig. 6 is a detail view of one of the end caps forming the end portion of the mandrel and over which the tube is crimped and folded; Fig. 7 is a side elevational view of a modified form of end construction; Fig. 8 is a sectional view, broken away in the middle, illustrating a modified form of end construction; and Fig. 9 is a top plan view, partly in 40 section, through the folded portion of the end construction shown in Figs. 7 and 8.

In the accompanying drawings I have shown a core of the sash weight composed of units of different specific gravities, but as 45 these form the subject-matter of a companion application filed of even date herewith, I shall not refer to them further than by saying that 1, 2 and 3 indicate units of different specific gravities, which units are 50 ranged in a tube 4. Tube 4 preferably consists of sheet metal and may be drawn as a single tube or formed by bending the plate and forming a longitudinal seam along the edges thereof. A cap piece 5, shown in Fig.

6, either hollow or solid as occasion demands, 55 is arranged inside the tube at the end of the column of units and preferably on top thereof, after which two side walls 4^a of the tube are crimped in against the cap piece, as shown in Fig. 5; this leaves the other two 60 side walls folded and extended at right angles to the walls 4^a, as shown at 4^b in Fig. 5. The folded projecting ends of the wall 4^b are now folded inwardly upon the walls 4^a, as indicated by the dotted arrows in Fig. 5, 65 this operation forming an end such as shown in Fig. 1. A clip 6 is now riveted to the folded ends of the tube, said clip being provided with an opening for the passage of the sash cord. This opening is only necessary 70 at one end of the weight but it is obvious that it can be provided at both ends if desired. The cap pieces 5 may be hollow, as shown in Fig. 6, or made solid, as shown in Fig. 8, in which latter instance the solid cap 75 piece will add weight to the structure.

Notwithstanding the fact that the shell or casing is of comparatively thin sheet metal, it will be observed by referring to Fig. 2 that the rivets which secure the cord clip 6 in position will pass through six thicknesses of metal constituting the folded end of the housing, and consequently a very strong and secure fastening for the cord clip is thus provided.

According to the modifications shown in 85 Figs. 7 to 9, inclusive, the folded portions 4^b at the ends of the tube are made to overlap each other, with the result that the thicknesses of metal at this point are increased to ten, which enables the use of a single hollow 90 rivet 7 which may be used as a cord-securing means or which may receive a ring 8 for this purpose, the ends of the ring being passed through the hollow rivet and bent laterally as shown in Figs. 7 and 8. In this modified 95 form I have shown also a central rod 9 having an eye embraced in the folded upper end of the shell or casing, and through which eye the hollow rivet 7 passes. This rod 9 may pass down through openings in the units and 100 have this lower end headed so as to engage the lower cap piece. In this manner should the shell or casing rust out or become unserviceable, the rod with the units strung thereon would still preserve the integrity of 105 the weight so that its usefulness would not be destroyed.

Having thus described the invention, what

is claimed as new and desired to be secured by Letters Patent is:

1. A sash weight composed of a core, end caps, and a shell or casing bent over said end caps and having portions of its end contacting with each other and connected together, said caps preventing the shell from bending inwardly; substantially as described.
2. A sash weight composed of a core, tapered end caps, and an inclosing shell or casing bent over said end caps and into intimate engagement with same and having its end portions connected together; substantially as described.
3. A sash weight composed of a rectangular core, pyramidal-shaped end caps arranged at the opposite ends of said core, and an angular tube or casing bent over said end caps and having its end portions connected together, said caps acting as stiffeners for the shell; substantially as described.
4. A sash weight composed of a core consisting of units, end caps so constructed as to add requisite weight to the structure, and an inclosing shell bent over said end caps to incase same and having its end portions connected together beyond said end caps, said caps acting to stiffen the shell and prevent it from bending; substantially as described.
5. A sash weight composed of a core, an inclosing casing consisting of a sheet metal shell having oppositely disposed portions of its ends bent and folded in upon each other to effect a complete closure, and a cord-seizing means extending over the folded end portions of said shell and secured thereto for holding them together; substantially as described.
6. A sash weight composed of a core, an inclosing shell or casing whose ends are bent and folded in to effect a closure, fastening devices passing through the folded portions of said shell for securing them together, and a clip-eye riveted to said folded ends; substantially as described.
7. A sash weight composed of a core, and an angular shell or casing inclosing said core and formed of sheet metal, two of the oppositely disposed side walls of said shell being bent inwardly so that they contact with each other, and the remaining oppositely disposed side walls of said shell being bent or folded inwardly and lapped upon the contacting portions of the first-mentioned walls whereby there are provided several thicknesses or layers of material at the extremities of said shell; substantially as described.
8. A sash weight composed of a core, and an angular inclosing shell or casing, two of the oppositely disposed side walls of the ends of which are bent in, and the remaining oppositely disposed side walls of said ends being bent inwardly and lapped upon the end portions of the first-mentioned walls so as to produce a pyramidal-shaped end consisting of several thicknesses or layers of material, and securing means passing through all of said superimposed layers of material; substantially as described.
9. A sash weight composed of a core, and an angular shell or casing inclosing said core and formed of sheet metal, two of the oppositely disposed side walls at one end of said shell being bent inwardly so that they contact with each other, and the remaining oppositely disposed side walls of said shell being bent inwardly and lapped upon the contacting portions of the first-mentioned walls so as to provide several thicknesses or superimposed layers of material at one end of the shell, and cord-seizing means passing through said superimposed layers of material; substantially as described.
10. A sash weight composed of a core, a rod passing through said core, an inclosing shell or casing whose ends are bent and folded in so as to provide several thicknesses of material, said rod having an eye in registration with said several thicknesses of material, and securing means passing through said eye, and said several thicknesses of material; substantially as described.
11. As a new article of manufacture, a sash weight consisting of a core composed of units, a rod passing through said units and provided with a head at its lower end for supporting said units, an inclosing shell or casing having portions of its ends bent into contact with each other and secured together, and cord-seizing means at the upper end of said rod; substantially as described.
12. As a new article of manufacture, a sash weight consisting of a core composed of units, a rod passing through said units and provided with a head at its lower end for supporting said units, an inclosing shell or casing connected to the upper end of said rod and having portions of its ends bent into engagement with each other and secured together, and cord-seizing means at the upper end of said rod; substantially as described.
13. A sash weight consisting of a core, and a shell incasing said core and formed of sheet metal, said shell having an approximately pyramidal-shaped end that is produced by bending or folding inwardly the end portions of the shell and securing them together; substantially as described.
14. A sash weight provided with a sheet metal shell having a closed end that is produced by bending or folding the material in the shell without cutting same so that two oppositely disposed portions of the shell are lapped upon two other oppositely disposed portions of the shell, and fastening devices passing through contacting portions of the shell to secure said folded portions together; substantially as described.

15. A sash weight provided with a sheet metal shell having a pyramidal-shaped end which is produced by bending or folding portions of the end of the shell inwardly upon 5 each other to provide several thicknesses of material, and means for clamping said folded portions together; substantially as described.

In testimony whereof I hereunto affix my signature in the presence of two witnesses, this twenty second day of October 1907.

FERDINAND C. SCHWEDTMAN.
